Des. 205,964
Patented Oct. 11, 1966

205,964

HOLDER FOR A PAIR OF EYEGLASSES

Dana Peterson, Box 412, Coronado, Calif. 92118

Filed Oct. 21, 1965, Ser. No. 87,699

Term of patent 14 years

(Cl. D57—1)

FIG. 1 is a perspective view of a holder for a pair of eyeglasses, showing my new design;

FIG. 2 is a rear elevational view thereof.

The side not shown, has substantially the same appearance as the side shown.

I claim:

The ornamental design for a holder for a pair of eyeglasses, as shown and described.
